United States Patent Office

Des. 215,892
Patented Nov. 4, 1969

215,892

MOVIE CAMERA OR SIMILAR ARTICLE

Richard J. Olson, 400 Plymouth Ave.,
Pittsford, N.Y. 14650

Filed June 13, 1968, Ser. No. 12,338

Term of patent 14 years

Int. Cl. D16—02

U.S. Cl. D61—1

FIG. 1

FIG. 2

FIG. 3

FIG. 1 is a front corner perspective of my design for a movie camera showing the front, top and one side thereof;

FIG. 2 is a front view thereof; and

FIG. 3 is a bottom perspective thereof from the diagonally opposite corner of FIG. 1 showing the back, bottom and another side thereof.

I claim:

The ornamental design for a movie camera or similar article, as shown.
